CARTRIDGE LOADING TOOL

Charles M. O'Neil, Hopkins, Minn.

Application November 14, 1936, Serial No. 110,878

5 Claims. (Cl. 86—23)

This invention relates to a tool for loading or reloading cartridges such as are used in hunting or target arms. Such devices are found to some extent for sale on the American market today and utilize a slidable cartridge case carrier which is moved forwardly or rearwardly from a central position by suitable means and which has associated therewith one or more dies which are operative usually to resize the exterior of the neck 5 of the cartridge case and in many instances to further resize the interior of the neck of the cartridge case by means of an expanding plug carried by the die and in many instances to further decap fired primers.

Such devices also are operative through the movement of the same carriage to load the neck of the cartridge shell with the projectile, a different die being utilized in this case. In addition to the foregoing functions such devices are 20 operative in many instances to reprime the cartridge case through the cooperative rearward movement of the cartridge case carriage and repriming mechanism including a priming pin associated with the said carriage and having movement relative thereto in the rearward movement 25 of the carriage.

The majority of such loading tools now utilized are not particularly rugged in character and as a result are not suitable for full length resizing 30 of the cartridge case. This is usually due to the flexibility of the frame and base of the tool and the connections between the cooperating working parts of the tool and the base.

Furthermore, such reloading tools for the most 35 part do not have satisfactory mechanism for assuring the alignment of the repriming mechanism with the primer pocket of the cartridge and objection has been found to the complicated primer feeding mechanism and the means for actuating 40 the same.

It is an object of my present invention to provide a much simplified, more compact and stronger cartridge loading tool than has heretofore been utilized and which may be manufactured at lower 45 cost while effectively resizing the full length exterior of the cartridge case.

It is a further object to provide a cartridge reloading tool which eliminates most of the working parts formerly required for feeding, progressively, 50 primers to the repriming mechanism and which positively assures perfect alignment of the repriming pin with the primer pocket of the cartridge case held in the retaining means of the cartridge case carriage.

Another object is the provision of cartridge re-

loading mechanism of the class described wherein all working parts are mounted within the rigid sides of a heavy channel member thus preventing flexibility of the base frame and of the connections between the base of the cartridge case carriage and the repriming and case retaining mechanism, as well as preventing flexibility of the parts which connect the operating mechanism and die-holding means with the base frame.

A still further object is the provision of a compact, rugged re-loading tool which will serve all the necessary functions including decapping of the used primer, reforming and resizing of the cartridge case, repriming of the case and loading 10 of the projectile into the neck of the forward 15 end of the cartridge.

These and other objects will be more apparent from the following description made in connection with the accompanying drawing wherein like reference characters refer to similar parts 20 throughout the several views, and in which:—

Fig. 1 is a side elevation of an embodiment of my improved cartridge reloading tool showing a cartridge shell operatively positioned for reforming and resizing the case as well as for decapping 25 the used primer, certain of the dotted lines indicating forward and rearward extreme positions of the operating lever;

Fig. 2 is a fragmentary top plan view of the device with the cartridge shell detached from the 30 cartridge case carriage;

Fig. 3 is a cross section taken substantially along the line 3—3 of Fig. 1, with the adapter and die removed;

Fig. 4 is a vertical section taken longitudinally 35 through the cartridge case carriage and the repriming mechanism along the line 4—4 of Fig. 2 and showing a cartridge shell operatively held in a position to have its rear end reprimed.

Fig. 5 is a top plan view of the primer carrying 40 sleeve detached, and

Fig. 6 is a detailed horizontal section showing the lost motion, slot and pin connection between the rear-end of the primer carrying sleeve and the priming rod.

As shown in the drawing I provide an elongated heavy base frame 7 of channel construction having attached to the top of its base portion and spaced from the sides thereof a T-rail 8 which, as shown, is constructed from a pair 50 of strips 8a and 8b, rigidly secured to the base of the channel and symmetrically arranged, the upper one 8b of which is wider and overhangs at its longitudinal edges the lower strip 8a.

A cartridge case carriage indicated as an en- 55

tirely by the numeral 9 is slidably mounted on the T-rail 8 having a T-shaped groove in the base portion thereof which receives the T-rail 8, permitting sliding movement of said carriage upon the rail in directions longitudinal of the base frame. The forward and upper end of the cartridge case carriage is recessed to receive a detachable U-shaped cartridge retaining member 10 similar in general construction to a cartridge extractor utilized in fire arms. This retaining member 10 precisely fits a complementarily shaped groove formed in the recessed upper and forward end of the case carriage and is retained in place as shown by engagement at one of its ends beneath a removable top plate 11 of the carriage and at its other end by a lock screw 12 (see Figs. 1 and 2) which has a retaining head cut on a straight line at one edge to release the engaged end of retaining member 10 when the head 20 is turned to a predetermined position. The top plate 11 as shown has a flat under surface which rests against the flattened top of the carriage proper and is secured thereto by a pair of clamping screws 13 which screws also secure an upper right primer magazine 14 to the top of the carriage. The primer magazine consists in a narrow tube of oblong cross section having an attachment base 14a which forms a flange having slots formed therein to accommodate the clamping screws 13 and to permit the slotted portions to be rigidly secured to the top of plate 11.

Novel and efficient priming mechanism is associated with and carried by the carriage 9. The carriage is provided with a relatively large vertical chamber 9a communicating at its upper end with an opening in the carriage directly back of the retaining member or extractor 10 which secures the base of the cartridge case and this chamber 9a is adapted to communicate with one or more discharge openings 15 formed through the T-rail 8 on which the carriage is mounted and also through the bottom of the base frame to enable removed primers to be discarded.

The upper portion of the carriage proper is drilled horizontally and longitudinally of the carriage to form a cylindrical passage for receiving a primer carrying sleeve 16 which is slidably mounted in such cylindrical passage for limited movement relative to the carriage. Carrying sleeve 16 has a longitudinal slot 16a formed in its upper portion in which the lower end of a stop screw 17 is accommodated, said stop screw limiting the relative movement of the carriage to the sleeve 16 by abutment with the ends of the said slotted portion. Sleeve 16 at its forward end is provided with a primer receiving aperture 16b of proper size and shape to accommodate a single primer disposed edgewise in the vertical magazine 14. The top portion of the carrying sleeve 16 is slotted adjacent the primer receiving aperture 16b the slots communicating with said aperture to assist in properly feeding the primers as will later be more fully described.

A horizontal priming rod 18 is telescoped within the carrying sleeve 16 and is mounted for limited longitudinal movement relative to the carrying sleeve 16. Priming rod 18 extends for some distance rearwardly of the rear end of sleeve 16 and carries an abutment head as shown of adjustable form comprising an enlarged abutment nut 19 with which is associated a lock nut 20. The forward face of the lock nut 20 is bossed to provide an annular shoulder for receiving a coiled reTRACTING SPRING 21 which is interposed between said lock nut and the rear of carriage 9, sur-

rounding the carrying sleeve 16. Within the rear portion of retraction spring 21 and snugly surrounding the rear portion of the priming rod is a coil sleeve-projecting spring 22, one end of which abuts the bossed face of the lock nut 20 and the opposite end of which abuts against the rear end of carrying sleeve 16, the purpose of this spring 22 being to normally project sleeve 16 to its limit of forward movement relative to the priming rod 18 which limit is determined by a lost motion connection between the rod 18 and sleeve 16 in the form of a pin 23 working in opposed limit slots 16c formed in the rear portion of tube 16 as shown clearly in Fig. 6. A stationary abutment in the form of a rigid arm or post 8c, as shown being bent up from the rigid upper plate 8 of the T-rail is positioned to engage the abutment head 19 of the priming pin during the rearward longitudinal movement of the carriage 9 to operate the priming and feeding mechanism in conjunction with the carriage movement.

To prevent accidental dropping of a primer from the forward end of carrying tube 16, in the event of a jar or jerk of the device, I provide suitable means to retain the primer in the sleeve 16 against forward displacement until the sleeve comes in contact, at its forward end with the base of the cartridge case. To this end small in-turned detents 16d are formed at the slotted forward end and upper portion of sleeve 16, the sleeve at this portion having sufficient resiliency to enable the primer to be projected from the sleeve and I further provide a light retaining spring 24 of the leaf type anchored to the carriage below sleeve 16 and having a free upper end, the extremity of which normally projects slightly above the inner periphery of the forward end of the sleeve at the bottom thereof. In the rearward movement of the carriage the spring, of course, yields and is disposed below the sleeve in a non-restricting position.

Hand operating means are provided for my tool in the form of a rigid operating lever 26 having an enlarged fulcrum end which is pivotally mounted on a heavy removable pin 27 which is seated and held in the two opposite sides or flanges of the rigid channel frame. A pair of rigid links 28 connect the rear of the carriage with lever 26 at points on said lever disposed a short distance above the fulcrum pin 27 of the operating lever. The two links 28 as shown are disposed at the side faces of the carriage 9 and are pivotally connected with the carriage by pins or trunnions 29 which receive apertured portions of the links and similarly the rear ends of the links are connected with pins 26a secured to the fulcrum end of lever 26 as shown spaces 26b being provided at opposite sides of the lever to hold the lever centrally of the channel base frame and to afford bearing surfaces for the rear ends of the links 28. I prefer to construct the link connections to eliminate the use of bolts, cotter pins and the like and to this end the links are urged together and thus retained upon their pivotal connections or trunnions by means of a heavy coil spring 30 which spans the links 28 and has its extremities connected with the two respective links.

The mechanism described up to this point is operative in itself to perfectly apply and attach a new primer in the primer pocket in the base of a cartridge case and such operation is performed by the rearward movement of the carriage 9 which is effected in the embodiment shown by 75

the rearward movement of the operating lever 26 indicated by the dotted lines in Fig. 1.

The forward movement of the cartridge case carriage of my tool may be utilized for several purposes, including the resizing of the cartridge case, both externally and internally at the neck and externally the reforming or resizing of the entire case as well as decapping or removing a used primer from the base of the case and also loading or applying the projectile to the case. The various dies used for decapping the primer, resizing externally and internally the cartridge case and loading the projectile now on the market can be utilized with my improved tool and a detailed description of such dies is therefore thought unnecessary. I do, provide, however, a die holder and adapter having distinct advantages in association and cooperation with the carriage and other working parts of my tool in contrast to similar parts now utilized extensively.

Since the dies now commercially available vary in length and in attachment means and since further my device is devised for loading cartridges of different sizes and caliber, I have found it desirable to provide die holding means including an adapter which will properly hold dies of various sizes and for various sized cartridges in proper operative position for cooperation with the carriage and cartridge retainer. To such end I provide an adjustable block 32, as shown in the form of a short inverted channel member of rigid construction, which block nicely fits between the sides or flanges of the channel base frame 1 and which is provided with oppositely aligned apertures in the sides thereof to accommodate a heavy removable retaining pin 33 which also is adapted to pass through any pair of a series of apertures 7a formed in the opposite walls of the channel base 7. In the top of block 32 is rigidly mounted a U-shaped receiving bracket 32a which is adapted to receive an annularly channeled retaining end which is formed in some dies of the class described. Bracket 32a is likewise constructed to receive a diminished connection portion 34a of an adapter 34 shown in Fig. 1. As shown, the connection portion 34a is provided by means of a headed bolt or the like secured at its inner end to one of the legs of the U-shaped adapter 34, but of course any suitable connection means having abutments adapted to straddle the front and rear faces of the bracket 32a and of such size as to nest within the U-shaped recessed portion of the bracket may be utilized. A forward depending leg of the adapter 34 is apertured and internally threaded at 34b to receive the externally threaded intermediate portion of certain dies D formed with such an external thread for connection with a die holder, the threaded connection of the die with my adapter serving to retain the die in perfect alignment with the cartridge case connected with the carriage 9, the insertion of the neck and forward portion of the cartridge case serving to perfectly center the parts for die operation on the case. A wide range of adjustment is provided with my die holder and adapter construction. The block 32 may be secured in several different positions relatively to the forward end of the base frame and screw threaded adjustment is provided in some dies having a channeled connection end construction which secures practically micrometer adjustment of the die. When the adapter is used with a die having an externally threaded intermediate portion, screw adjustment is provided in the con-

nection of said portion with the forward depending leg of my adapter 34.

Operation

In reloading a fired cartridge case with my tool, the used primer is first expelled and the case resized. These two operations may be simultaneously carried out with my tool, in which instance a suitable die D of conventional type having an expanding plug within the forward end thereof 10 for resizing the interior of the cartridge neck as well as a die for externally resizing the entire cartridge shell with the exception, of course of the base, is utilized. My die holder and adapter, if the latter is needed are properly adjusted to position the forward end of the die properly to receive the cartridge case. This is accomplished by inserting a used cartridge case in the die by hand, then swinging the operating lever 26 to full forward position with the base flange of 20 the cartridge case operatively connected with the retaining member 10 to the proper position of the die. The die is then secured to the die holder or adapter as the case may be and lever 26 is swung back sufficiently from extreme forward position to 25 admit the combined cartridge case and adapter. Subsequent swinging of lever 26 to extreme forward position then completely resizes the exterior surface of the cartridge case as well as resizing internally the neck, and with a de-capping pin 30 applied to the interior of the die, removes the used cap during the resizing operation.

To reprime the cartridge case it is merely necessary to swing the lever 26 backward to extreme rearward position which moves carriage 9 35 rearwardly and also causes the re-capping rod 18 and primer carrying sleeve 16 to be carried rearwardly with the carriage until the abutment head 19 on the re-capping rod strikes the upturned stationary abutment 8c, at which time the 40 continued rearward movement of the carriage causes relative forward movement on the part of the carrying sleeve 16 which contains a new primer into the forward end of sleeve 16, engages the base of the cartridge case. Further 45 rearward movement of the carriage in view of the lost motion connection between pin 23 and the carrying sleeve 16 causes the priming rod 18 to project the primer into the primer pocket of the cartridge case while enabling the forward 50 end of the carrying sleeve to continue to engage the portion of the base of the cartridge surrounding the pocket without producing further movement of the sleeve relative to the base of the cartridge. In the repriming movement of the sleeve 55 16 and the priming rod 18 the priming rod acts as a shut off for the bottom of the primer magazine preventing the next primer from entering the sleeve until the sleeve and priming rod are retracted to the position shown in Fig. 4 which 60 is the feeding position. The next primer resting on the top of the priming rod is accommodated in the narrow slot 16a formed in the carrying sleeve rearwardly of the primer feed opening.

What is claimed is:—

1. In a cartridge loading tool, a base frame, a cartridge case carriage mounted for longitudinal sliding movement on said base frame, said carriage having its forward end provided with means for retaining a cartridge shell and automatically 70 fed, repriming mechanism comprising, a primer carrying sleeve mounted in the upper portion of said carriage for limited sliding movement longitudinally of said carriage and being axially aligned with said cartridge case retaining means 75

and having a primer receiving opening in the top portion thereof adjacent its forward end, a primer magazine secured to the top of said carriage and extending upwardly therefrom in communication with the interior of said carrying sleeve in a predetermined position of said sleeve relative to said carriage, a re-priming pin slidably mounted within said carrying sleeve and axially aligned therewith and means for abutting the outer end of said re-priming pin when the same has been moved by said carriage a predetermined distance rearwardly, whereafter further movement of said carriage rearwardly will cause said carrying sleeve and said re-priming pin to be projected forwardly relative to said carriage.

2. In a cartridge loading tool, a base frame, a cartridge case carriage mounted for longitudinal sliding movement on said base frame, said carriage having its forward end provided with means for retaining a cartridge shell and automatically fed, repriming mechanism comprising, a primer carrying sleeve mounted in the upper portion of said carriage for limited sliding movement longitudinally of said carriage and being axially aligned with said cartridge case retaining means and having a primer receiving opening in the top portion thereof adjacent its forward end, a primer magazine secured to the top of said carriage and extending upwardly therefrom in communication with the interior of said carrying sleeve in a predetermined position of said sleeve relative to said carriage, a re-priming pin slidably mounted within said carrying sleeve and axially aligned therewith, means for abutting the outer end of said re-priming pin when said pin has been moved by said carriage a predetermined distance rearwardly, whereafter further movement of said carriage rearwardly will cause said carrying sleeve and said re-priming pin to be pro-

jected forwardly relative to said carriage, a lost motion connection between said carrying sleeve and said repriming pin permissive of limited relative longitudinal movement of said pin and sleeve, and means for urging said sleeve to its limit of movement forwardly of said pin.

3. The structure set forth in claim 2, and means for urging retraction of said re-priming pin rearwardly of said carriage.

4. In a cartridge loading tool, a rectilinear base frame of rigid construction, a cartridge case carriage slidably mounted upon said base frame for longitudinal movement thereof, the forward end of said carriage having cartridge retaining means engageable with the base of a cartridge case, an attachment block adapted to be fixed to said frame forwardly some distance of said carriage, said block having an attachment bracket adapted to receive an annularly shouldered member such as a cartridge reforming die, a liftably removable adapter having a rearwardly extending annularly shouldered member adapted to be received and secured to said bracket and having a forward portion internally screw-threaded to receive an externally screw-threaded portion of a die, said adapter having a centrally disposed recess for accommodating the body of the die, said internally screw-threaded portion being axially aligned with the cartridge case retaining means upon said carriage.

5. The structure set forth in claim 4, where in said adapter constitutes a rigid inverted U-shaped member, the forward leg of which rigidly carries an annularly channeled element, and the rearward leg of which is provided with said internal die-receiving thread, the inverted base of the U being spaced some distance above a die secured to said leg to accommodate the body of said die.

CHARLES M. O'NEILL.
